UNITED STATES PATENT OFFICE.

WILLARD H. SMITH, OF NEW YORK, N. Y.

VENTILATOR FOR WATER-CLOSETS OF RAILWAY-CARS AND OTHER CONVEYANCES.

SPECIFICATION forming part of Letters Patent No. 224,484, dated February 10, 1880.

Application filed December 10, 1879.

To all whom it may concern:

Be it known that I, WILLARD H. SMITH, of the city, county, and State of New York, have invented certain new and useful Improvements in Ventilators for Water-Closets of Railway-Cars and other Conveyances, of which the following is a specification.

My invention, while applicable generally to the water-closets of land and water conveyances, has been designed with particular reference to railway-cars, and in that connection it will here be described.

When a railway-car is in rapid motion there is a tendency, particularly when roof-ventilators are used, to a vacuum in the car, a draft being thus established which causes at times a strong current of air to pass upward through the water-closet of the car, carrying with it waste-paper and bringing with it quantities of dust.

This difficulty has been the cause of frequent annoyance, and attempt has heretofore been made to overcome it.

I have found that the trouble referred to can be readily and effectually remedied by providing the water-closet, at or near its lower end, with a ventilator or exhaust-passage, which opens to the rear relatively to the motion of the car, and serves to establish through the closet-funnel a downward draft, which obviates the difficulty hereinbefore referred to.

Various means may be employed to carry my invention into effect.

In the accompanying drawings I have indicated a few of the many devices that may be used for the purpose.

Figure 1 is a perspective view of a railway-car water-closet provided with ventilating appliances in accordance with my invention. Fig. 2 is a longitudinal vertical central section of the same. Fig. 3 is a horizontal section through the ventilating flue or passage.

The water-closet proper, A, may be of any approved construction, with its tubular body extending down through the floor of the railway-car. Below the car-floor this tubular body is provided in its side with draft-openings *a b*, each opening into a horizontal tube or funnel, B, which extends longitudinally of the car. It is through these funnels and openings that the draft is established, which pre-

vents upward currents of air through the closet funnel or seat.

Supposing the car to be moving in the direction of the arrow in Fig. 3, then the front opening, *a*, should be closed, and the rear opening, *b*, left open. The motion of the car establishes a draft through *b* and its funnel B, which causes a downward current in the closet sufficient to carry off all waste-paper and offensive smell, and to prevent dust from entering the car through the closet to any extent. When the car moves in the contrary direction the opening *b* should be closed and *a* should be opened—in other words, that end of the ventilating-flue which is in front relatively to the movement of the car should be closed, while the opposite end should be open. Various mechanical devices may be used for this purpose.

Two arrangements are shown in the figures hereinbefore referred to. In the one arrangement a rotary gate, C, fitting within the tubular body of the closet, is provided with ports or openings *c d*, so formed and arranged that when the one port is opposite one of the openings in the closet-body a solid portion of the gate will be opposite to and close the opposite opening in the closet-body, as indicated plainly in Fig. 3. The rotary gate can readily be operated by any suitable means—as, for instance, by a crank-shaft, *e*, which extends inside the car, and is provided with a handle, *e'*, by which it may be turned, and at its lower and outer end is provided with a crank-arm, which enters a slotted bracket-arm, *f*, fast to the rotary gate.

In lieu of the rotary-gate arrangement I can employ doors *g* on the ends of the draft funnels or flues B, which can be closed or opened, as the case may be, according to the direction in which the car moves. In this case, perhaps, waste-paper might accumulate in the closed front flue or funnel, B; but this tendency can partly be neutralized by connecting the funnels to a suitable flue, *h*, which extends upward to and above the roof of the car.

In lieu of employing a rotary sliding gate for closing the openings *a b*, I can use swinging doors for the purpose, as shown in Figs. 4, 5, and 6.

Fig. 4 is a longitudinal vertical central sec-

tion of a closet containing the modification. Fig. 5 is a plan, partly in horizontal section, of the same. Fig. 6 is a horizontal section through the lower portion of the closet-body. Fig. 5. The said lower portion of the closet-body is in this instance rectangular in cross-section. Its draft-openings *a b* are provided with hinged doors *i*, one of which should be closed when the other is open. For this purpose each is provided with a pin, *j*, which projects through and works in a curved slot, *k*, in the closet-frame, and is connected by a link, *l*, to the crank-arm *m* of a shaft, *n*. When the crank-shaft *n* is turned it will, in closing one door, open the other.

A bow-spring, *o*, or other friction device may be used to hold the parts securely in either position of adjustment. Having described my invention, I would say, in conclusion, that I do not confine myself to the mechanical details herein shown in illustration of the same; but

What I do claim, and desire to secure by Letters Patent, is—

1. The combination, with the water-closet 25 of a railroad-car or other conveyance, of a ventilating flue or passage at or near the lower end of the same, and means, substantially as described, whereby that end of said flue or passage which is in front relatively to the movement of the car may be closed, substantially as and for the purpose set forth.

2. The combination, with the tubular closet-body provided with the front and rear draft-openings, of a draft flue or funnel for each opening, and doors by which said openings may be closed at pleasure, substantially as and for the purposes set forth.

In testimony whereof I have hereunto set my hand this 3d day of December, 1879.

WILLARD H. SMITH.

In presence of—

COLERIDGE A. HART,

HORACE E. DEMING.
